UNITED STATES PATENT OFFICE

DANIEL DAILEY, OF NEW YORK, N. Y.

IMPROVEMENT IN DUMPING-SCOWS.

Specification forming part of Letters Patent No. 173,847, dated February 22, 1876; application filed January 22, 1876.

To all whom it may concern:

Be it known that I, DANIEL DAILEY, of the city, county, and State of New York, have invented a new and Improved Dumping Scow, of which the following is a specification:

In the accompanying drawing, Figure 1 represents a top view, Fig. 2 a vertical longitudinal section on the line *c c*, Fig. 1, and Fig. 3 a vertical transverse section on line *x x*, Fig. 2, of my improved dumping-scow.

Similar letters of reference indicate corresponding parts.

My invention relates to an improved dumping-scow, from which the refuse may be more readily and conveniently dropped for submergence than in the present systems of scows; and it consists of a scow divided by a longitudinal center bulk-head and lateral brace-walls into compartments, which are each closed by hinged bottom gates that are raised or dropped by chains winding on a top shaft.

In the drawing, A represents a dumping-scow, which is divided into two symmetrical sections by a center bulk-head, B, that extends longitudinally through the full length of the scow. The interior storage part of the scow is divided by lateral walls and braces C into smaller compartments. Each compartment, or, preferably, two or more adjoining ones at the same side of the center bulk-head, according to their size, are closed by double bottom gates D, of which one is hinged or hung by chains to the center bulk-head B, the other to the side wall or bulk-head of the scow. A longitudinal shaft, E, is supported in central bearings of the lateral walls, and operated by a hand-lever crank, windlass, or other wind-

ing-up device, being retained by means of ratchet-wheel and pawl. The double gates of each compartment are connected by chains E' to the shaft E, one chain branching out to both gates, and being affixed near the ends of the gates, serving to drop or close jointly both gates of a compartment. The gates of adjoining compartments on either side of the center-board may be connected to one shaft, so that a certain number of compartments may be emptied simultaneously by releasing the shaft. The gates are a suitable distance below the lateral braces of the scow, which, together with openings at the after end of the scow, admit the entering of the water, and thereby the sweeping of the same through the scow, which facilitates, when all the gates are dropped, the submerging of the refuse, and the carrying away of the scum or lighter parts. The smaller size of the compartments admits the easier handling of the gates, and thereby their readier and quicker emptying, so that the scow requires a less number of hands, and is attended to with greater facility and dispatch.

Having thus described my invention, I claim as new and desire to secure by Letters Patent—

A garbage scow, separated longitudinally by a close and transversely by open-work partitions, having sides perpendicular, and provided with several hinged gates at bottom, as and for the purpose specified.

DANIEL DAILEY.
